FEEDING BOX

Montie A. Wallace, Sanderson, Tex.

Application February 28, 1939, Serial No. 259,031

3 Claims. (Cl. 298—7)

This invention aims to provide a simple but effective device, adapted to be used in distributing feed to animals on a range, the dispensing of the feed being under the control of the driver of a vehicle, and it being unnecessary to have an extra hand to pitch off the feed at places where the feed is needed. The invention aims, further, to improve the construction of the body of the article, and to provide novel means for mounting 5 and operating the gate which controls the feed-flow.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in longitudinal section, a device constructed in accordance with the invention;

Fig. 2 is a rear end elevation;

Fig. 3 is a section on the line 3—3 of Fig. 1;

Fig. 4 is a fragmental bottom plan;

Fig. 5 is a section on the line 5—5 of Fig. 1.

The numeral 1 marks the platform of a truck or other vehicle, one side of the platform being designated by the numeral 2. The device forming the subject matter of this application generally is so placed on the platform 1 as to discharge crosswise of the vehicle, at the side 2, but to avoid confusion, such terms as "front", "back" and the like, will be used relatively to the direction of the flow of feed in Fig. 1, as per arrow A, and not relatively to the direction in which the vehicle advances.

A box-like body B, open at the top and bottom, is securely mounted on the platform 1. The body B includes a vertical front wall 3, a vertical rear wall 4 having an opening 5 in its lower edge, and vertical side walls 6. A downwardly and rearwardly inclined bottom 7 is secured in the body B and occupies the entire horizontal cross section 50 of the body. The bottom 7 has a reduced tongue 8, extended through the opening 5 in the rear wall 4, and to the tongue 8 are secured the vertical side pieces 9 of a spout. The spout as a whole is marked by the reference character S. The upper portions of upper partitions 10 are secured

to the side walls 6 and slant downwardly and inwardly, as shown in Fig. 3, the partitions 10 extending between the front wall 3 and the rear wall 4 of the body B. The lower edges of the upper partitions 10 engage the upper edges of 5 vertical, parallel lower partitions 11 secured to the bottom 7, the lower partitions 11 extending between the front wall 3 and the rear wall 4 of the body B.

Located within the compartment formed by 10 the bottom 7, the rear wall 4 and the front wall 3 of the body B is a metal lining 12, conforming to the partitions 10 and 11 and extended along the bottom 7. The lining 12 is trough-shaped in cross section, but its ends are closed by the walls 15 4 and 3 of the body B. The lining 12 is supplied at its upper edges with hook flanges 14, engaged over the upper edges of the side walls 6 of the body B. The bottom of the lining 12 has a tongue 15, resting on the tongue or bottom 8 of the 20 spout S.

A trough-shaped spout extension 16 is provided, and is pivotally mounted at 17 on hanger brackets 18, secured to the lower surface of the bottom 8 of the fixed spout S. The spout extension 16 25 is provided on one side with longitudinally spaced ears or keepers 19, shown in Fig. 4. A retainer, such as a hook 20, is pivoted to one side piece 9 of the fixed spout S. The hook 20 may be engaged with one of the keepers 19, to hold the 30 bottom of the spout extension 16 aligned with the bottom 7 of the feed compartment in the body B to facilitate a feed run-off and delivery, in the direction of the arrow A in Fig. 1. The run-off of feed is under the control of a gate 21, 35 to be described hereinafter. The gate 21 holds the feed in the feed compartment but even when the gate is closed, as in Fig. 1, some feed may sift under the lower edge of the gate. The spout extension 16, however, may be turned up into 40 the dotted line position of Fig. 1, to retain in the fixed spout S, any feed that may sift under the gate 21, and the spout extension 16 may be held in the upright position of Fig. 1, by engaging the hook 20 with the appropriate one of the keepers 45 19 on the sides of the spout extension.

As shown in Fig. 2, cleats 22, of considerable height, are secured to the rear wall 4 of the body B, the cleats extending outwardly to the outer edges of the body. The inner ends of the cleats 50 22 are spaced apart to provide a vertical guideway 23 on the outer surface of the rear wall 4 of the body B. It is in the guideway 23, that the aforesaid gate 21 is mounted for vertical reciprocation.

The gate 21 is sharpened at its lower edge, as shown at 24, in order that the gate may slice down readily into the flowing feed and cut it off. The gate 21 slides ahead of an upper cross piece

5 25 and a lower cross piece 26, which may be angle members, and securing elements 27, such as bolts, hold the cross pieces 25-26 on the cleats 22, and hold the cleats 22 on the rear wall 4 of the body B, the cross pieces 25 and 26 extending 10 across the guideway 23.

The gate 21 is adapted to be raised and lowered by a mechanism to be described herein-after. The amount that the gate 21 is raised, and the amount of feed delivered in a given time 15 are regulated by a stop 28 on the gate 21, the stop being adapted to come into contact with the upper cross piece 25. The amount that the gate 21 is raised, may be regulated by changing the position of the stop 28, vertically, and this 20 can be done because the gate 21 has vertically spaced openings 29, in any of which may be mounted a securing element 30 which holds the stop 28 on the gate 21. The gate 21 is drawn down to closed position by a pull spring 31, having 25 its lower end anchored on the lower cross piece 26, the upper end of the pull spring being attached to the gate 21 by a securing element 32, mounted in the gate. In order that the securing element 32 and the securing element 30 for the 30 stop 28 may have a secure mounting in the gate, an anchor plate 33, shown in Fig. 1 is let into the gate 21, the securing elements 30 and 32 being threaded into the anchor plate.

As to the means for raising the gate 21, against 35 the pull of the spring 31, a bell crank lever 34 is fulcrumed at 35 on one of the cleats 22 and has an elongated slot 36, receiving the securing element 32 on the gate. To the upper end of the bell crank lever 34 is attached a draw line 37, 40 which may be prolonged forwardly to the driver's seat (not shown) on the vehicle that carries the body B.

The operation of the structure is simple. The driver pulls on the draw line 37, the bell crank 45 lever 34 is tilted on its fulcrum 35, the gate 21 is raised, and as much feed as the attendant wishes, comes out of the feed compartment, by way of the fixed spout S and the spout extension 16. When the draw line 37 is slackened away, the 50 gate 21 assumes closed position, and cuts off the flow of feed, under the impulse of the pull spring 31.

The device affords a convenient way for dispensing feed from a vehicle, it being unnecessary for a person to stand on the vehicle and heave off the feed.

The specific mounting of the gate 21 and the 5 feed compartment construction are useful features of the device.

What is claimed is:

1. A dispensing device for vehicles, comprising a body including a rear wall having an opening, the body comprising an inclined bottom leading to the opening, cleats on the rear wall and defining a guideway above the opening, upper and lower cross pieces attached to the cleats and extended across the guideway, a gate retained by 15 the cross pieces in the guideway for sliding movement, a securing device mounted on the gate, a gate-closing pull spring connected to the securing device and to the lower cross piece, a stop on the gate and cooperating with the upper 20 cross piece to limit the opening movement of the gate, and means connected to the securing element, and under the control of an operator, to bring about an opening of the gate.

2. A dispensing device for vehicles, comprising 25 a body including a rear wall having an opening, the body having an inclined bottom leading to the opening, a gate controlling the opening, means for mounting the gate for sliding movement, including upper and lower cross pieces, a 30 gate-closing pull spring connected to the lower cross piece and to the gate, a stop cooperating with the upper cross piece to limit the opening of the gate, means for mounting the stop on the gate in adjusted positions with respect to the 35 upper cross piece, and means under the control of an operator for opening the gate.

3. A dispensing device for vehicles, comprising a box-like body including side walls, a front wall, and a rear wall having an opening, the body including 40 an inclined bottom leading to the opening, and having a tongue extended through the opening, a lining in the body and supported on the bottom, the lining being trough-shaped and being closed at its ends by the front and rear walls and 45 extending upwardly on the side walls, the lining having a tongue, prolonged through the opening and supported on the tongue of the bottom, and a gate movably mounted on the rear wall and controlling the opening. 50

MONTIE A. WALLACE.
